(57) **CLAIM**

The ornamental design for a foldable sofa bed as shown and described.

DESCRIPTION

FIG. 1 is a perspective view of a foldable sofa bed showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of portion 9 in FIG. 2.

The dot-dash broken lines in FIGS. 2 and 9 depict boundary lines of the enlargement views and form no part of the claimed design.

1 Claim, 9 Drawing Sheets
